TANK SECURING MEANS

Filed April 10, 1928

INVENTOR
Charles Wm Mitzenius
BY *F. A. Libby* ATTORNEY

UNITED STATES PATENT OFFICE.

CHARLES W. MITZENIUS, OF JERSEY CITY, NEW JERSEY, ASSIGNOR TO AMERICAN CAR AND FOUNDRY COMPANY, OF NEW YORK, N. Y., A CORPORATION OF NEW JERSEY.

TANK-SECURING MEANS.

Application filed April 10, 1928. Serial No. 263,998.

Reference is had to the accompanying drawings which illustrate the preferred form of the invention; though it is to be understood that the invention is not limited to the exact details of construction shown and described, as it is obvious that various modifications thereof within the scope of the claims will occur to persons skilled in the art.

10 In the drawings:

Figure 1 is a top plan view of the device, showing a tank in section secured thereby;

Fig. 2 is a side elevation of the device shown in Fig. 1, certain parts being shown 15 in section, the view being taken on the line 2—2, Fig. 1;

Fig. 3 is a sectional view on the line 3—3 of Fig. 2; and

Fig. 4 is a sectional view on the line 4—4 20 of Fig. 1.

This invention relates to a means for securing tanks or the like to a support which may be a railway car or other carrier, and has particular reference to a clamping means 25 for said tanks.

One object of the invention is the provision of a simple and inexpensive clamping device.

Another object of the invention is the provision of oppositely acting clamp elements 30 adapted to secure tanks or other containers to a carrier such as a railway car or the like.

While the present invention is particularly designed for use with railway cars, such, 35 for example, as the gondola type, the construction of such cars forms no part of the present invention, and hence no details thereof are illustrated. I am aware that it is old in the art to provide multi-unit tank cars and 40 I make no claim to such a broad concept.

The present invention is designed particularly for the retention of vertically arranged tanks in or to a suitable carrier, and to that end, the invention contemplates the provision of spaced channel girders indicated at 45 2 and 3 respectively, girder 2 being supported intermediate its ends by suitable standards 4 (see Fig. 3), the lower ends of which standards are secured to the carrier (not shown). The girder 2 is also secured at its ends to the carrier and is riveted to the standards as at 50 6. As clearly shown in Figs. 1 and 2, the girders are arranged in spaced relation whereby to receive between them suitable

tanks 8; the tanks being vertically positioned as clearly indicated in Fig. 2.

The securing means for the tanks are carried by the several girders, and referring now to girder 2, it can be seen that the said securing means comprises a clamping assemblage including a base portion or mount 10 having horizontally arranged attaching ears 12 by which the base portion is secured through the medium of rivets 14 or the like. In practice, the base portion is preferably 65 provided with depending lugs 15 which are adapted to enter suitable apertures in the girder 2 whereby to position the base portion. The base portion is provided with oppositely arranged vertical ribs 16 extending 70 transversely of the girder and each provided with an extended head 18 defining spaced guideways 20 within which oppositely facing clamp elements 22 and 24 respectively are arranged for horizontal movement. 75

Intermediate the ends of the ribs 16 and preferably formed integral therewith is a backing plate 26 against the opposite faces of which the heads 27 and 29 of operating screws 28 and 30 are adapted to work. The 80 screws 28 and 30 are provided with annular bearing surfaces 32 and 34 respectively adjacent the respective heads, which bearing surfaces are seated in recesses 36 provided in bearings 38 formed integral with the base 85 portion 10 on each side of the backing plate 26. The screws, as above implied, face in opposite directions and have threaded engagement with the clamps 22 and 24 for actuating the latter; the screws extending into 90 threaded sockets 40 and 42 respectively, of the clamps 22 and 24.

The clamps each comprise an upper portion 44 having a head 46 the face of which is arcuate shaped to engage the outer surface of a cylindrical tank. The side edges 48 of the upper portion of the clamps converge rearwardly and are connected by webs 50 extending to the sockets 40 and 42 respectively, whereby to form a unitary structure. The clamps also include a base or guiding portion, the same comprising spaced guide rails 52 the lower edges of which are offset as at 54 to be positioned under the heads 18 of the ribs 16, and in the oppositely arranged guideways 20, as will be obvious from Fig. 4; the offset portions 54 defining angular recesses 56 into each of which a screw

58 extends. The screws 58 serve as stop elements for limiting the forward movement of the clamps; the latter being provided with integral abutments 60 at the rear ends of the rails 52, as shown more clearly in Fig. 1. For reinforcing purposes and to provide a unitary structure oppositely arranged rails 52 are connected by transverse ribs 62 formed integral with said rails and with the sockets 10 40 and 42 respectively.

The description just above refers particularly to the construction of the clamp assemblage secured to the girder 2 and said assemblage is employed intermediate the ends of 15 the carrier whereby to engage a tank positioned on each side of the girder. At the ends of the carrier, it is apparent that opposed clamps are not required; only one being necessary, and the girder 3 is shown as being secured to either a standard 64 or the upper 20 surface of the carrier end. A clamp mount is secured to the girder, the same including the attaching ears 66 which receive rivets 68. The mount comprises the side walls 70 having 25 the heads 72 which define guideways 74 within which the clamp 76 is horizontally movable. The clamp is in all respects similar to those heretofore described so the same characters of reference are applied thereto 30 and the same description is applicable. This is a single clamp assemblage, however, and the side walls 70 are connected by an end plate 78 serving as a backing plate in a manner similar to that described above with reference 35 to the backing plate of the assemblage shown on girder 2.

As before-mentioned, the clamp assemblages are mounted on transverse girders secured to a carrier; the latter being adapted to 40 receive vertical tanks to be supported thereby. Prior to the placing of the tanks on the carrier, the clamps are withdrawn from their extended positions by means of a suitable tool which engages the heads of the screws 45. The tanks may then be positioned between oppositely arranged clamp assemblages and the clamps then actuated by means of the screws to engage the heads of said clamps with the outer surfaces of the tanks whereby 50 to secure the tanks to the carrier. It will be apparent that the clamps are forced outwardly due to the engagement of the heads of the screws with the backing plates. It will also be seen that to withdraw the clamps, a reversal of the screws is necessary, the under 55 surfaces of the heads binding against the bearings thereby retaining the screws against horizontal movement and effecting a backing up of the clamps. It is believed that the construction and operation of the device will be 60 fully apparent to those skilled in the art from the above description when considered in conjunction with the drawings, and it is further believed apparent that those skilled in the 65 art will recognize that a simple, inexpensive,

strong and durable clamping means for securing vertical tanks to a carrier has been provided.

What is claimed is:

1. Means for securing a tank or the like to 70 a carrier comprising oppositely arranged clamp elements for engaging said tank, a base portion supporting said elements on which they are horizontally movable, an actuating screw for each element provided with a 75 head, bearings supporting said screws and with which the heads are adapted to contact to limit horizontal shifting of the screws in one direction when the latter are actuated to retract the clamp elements, and a backing 80 plate on each base portion for limiting horizontal shifting of the screws in the opposite direction when the latter are actuated to project the clamp elements.

2. A device of the kind described comprising 85 means for securing tanks or the like to a carrier including standards, girders secured to the standards, oppositely arranged clamp elements for engaging the outer surfaces of a pair of spaced tanks, said elements being movable horizontally, oppositely extending actuating screws for the clamp elements, bearings supporting said screws and limiting horizontal shifting of the screws in one direction, and a backing plate interposed between 90 the ends of said screws for limiting horizontal shifting of the latter in the opposite direction.

3. A device of the kind described comprising 100 a clamp assembly including a base portion, oppositely arranged clamp elements horizontally movable on the base portion to be retracted and projected, oppositely extending actuating screws for the clamp elements, bearings supporting said screws and limiting horizontal movement of the screws when the latter are actuated to retract the clamp elements, and a backing plate common to said screws and with which the ends of the latter are adapted to contact to limit horizontal 105 shifting thereof when the screws are actuated to project the clamp elements.

4. A device of the kind described comprising 110 a clamp assembly including a base portion, oppositely arranged clamp elements horizontally movable on the base portion to be retracted and projected, oppositely extending actuating screws for the clamp elements, bearings supporting said screws and limiting horizontal movement of the screws when the latter are actuated to retract the clamp elements, and cooperating means on the base portion and clamp elements to limit the projection of the latter.

5. A securing means for tanks or the like 115 comprising standards adapted to be secured to a carrier, a girder secured to the standards, a clamp mount secured to the girder and provided with spaced guideways, a backing plate 120 extending between the guideways interme- 130

diate the ends thereof, oppositely extending clamps movable in the guideways and having a tank engaging head and a socket, a bearing member on each side of the backing plate, and 5 operating screws mounted in the bearings and threadedly engaged in the sockets, said screws having actuating heads arranged between the bearings and backing plate to engage said bearings and backing plate upon actuation 10 whereby to retain the screws in position to actuate the clamps.

6. A securing means for tanks or the like comprising a clamp assembly having a base portion, guideways on said base portion, oppositely arranged clamp elements supported by the base and movable in the guideways, said clamp elements each having a head portion for engaging a tank, a base portion and a socket, oppositely extending operating screws 15 for the clamps engaged in the sockets for actuating the clamp elements to retract or project the latter, and means for retaining the operating screws against substantial horizontal movement during operation thereof.

20 7. In a device of the kind described, a clamp assembly comprising a base portion, guideways on the base portion, a clamp element mounted on the base portion for movement

in the guideways, and provided with an arcuate face for engaging a tank and a threaded 30 socket, a bearing on the base portion, an operating screw mounted in the bearing and extending into the socket, an actuating head for the screw, an abutment formed on the base portion with which the actuating head contacts upon rotation of the screw to project the clamp element, and a stop element for limiting the projection of the clamp element.

8. A device of the kind described comprising a clamp assembly including a base portion, oppositely arranged clamp elements horizontally movable on the base portion to be retracted and projected, oppositely extending actuating screws for the clamp elements, bearings supporting said screws and 40 with which said screws contact upon rotation of the latter whereby the clamp elements are retracted on the screws, and a backing plate common to both screws and with which the said screws contact upon opposite rotation thereof to project the clamp elements on 45 said screws to clamping position.

In witness whereof I have hereunto set my hand.

CHARLES WM. MITZENIUS.
